(57) **CLAIM**

The ornamental design for a spot light for stage lighting as shown and described.

DESCRIPTION

1. Spot light for stage lighting
2. Spot light for stage lighting
- 1.1 : Side view of a spot light for stage lighting
- 1.2 : Front view of the spot light for stage lighting of Fig. 1.1
- 1.3 : Side view of the spot light for stage lighting of Fig. 1.1
- 1.4 : Back view of the spot light for stage lighting of Fig. 1.1
- 1.5 : Top view of the spot light for stage lighting of Fig. 1.1
- 1.6 : Perspective view of the spot light for stage lighting of Fig. 1.1
- 2.1 : Right view of a spot light for stage lighting
- 2.2 : Back view of the spot light for stage lighting of Fig. 2.1
- 2.3 : Left view of the spot light for stage lighting of Fig. 2.1
- 2.4 : Front view of the spot light for stage lighting of Fig. 2.1
- 2.5 : Top view of the spot light for stage lighting of Fig. 2.1
- 2.6 : Perspective view of the spot light for stage lighting of Fig. 2.1

The broken lines depict portions of the spot light for stage lighting that form no part of the claimed design.

1 Claim, 12 Drawing Sheets
